UNITED STATES PATENT OFFICE

THOMAS J. FEGLEY AND GEORGE O. LEOPOLD, OF PHILADELPHIA, PENNSYLVANIA,
ASSIGNORS TO NORTH BRO'S M'F'G CO., OF PHILADELPHIA, PENNSYLVANIA, A
CORPORATION OF PENNSYLVANIA

DESIGN FOR AN ICE CUBE BREAKER

Application filed July 29, 1931. Serial No. 40,718. Term of patent 7 years.

To all whom it may concern:

Be it known that we, THOMAS J. FEGLEY and GEORGE O. LEOPOLD, citizens of the United States, residing in Philadelphia, Philadelphia County, Pennsylvania, have invented a new, original, and ornamental Design for an Ice Cube Breaker, of which the following is a specification, reference being had to the accompanying drawing, forming part thereof,

in which the figure is a perspective view of the ice cube breaker embodying our new design.

We claim:

The ornamental design for an ice cube breaker, substantially as shown.

THOMAS J. FEGLEY.
GEORGE O. LEOPOLD.
